SPRING MATTRESS

William Lewis, Utica, N. Y.

Application January 31, 1933, Serial No. 654,451

4 Claims. (Cl. 5—252)

This invention relates to a spring mattress in which a multiplicity of tapered coil springs are attached at their smaller ends to a suitable supporting frame to extend outwardly or upwardly therefrom in more or less uniformly spaced parallel relation with their outer ends in substantially the same plane parallel with that of the frame for receiving and supporting an upholstered or equivalent mattress, the outer edges 10 of the larger ends of the coils being connected to a resilient marginal rail to hold them against relative lateral movement and at the same time permitting them to yield axially under varying pressures.

15 The coil springs of this mattress are preferably arranged so as to constitute what may be termed an outer marginal set and an intermediate or inner set and one of the objects of the invention is to make the springs of the inner set considerably longer than those of the outer set and to depress the intermediate portion of the main frame a corresponding distance beyond the plane of the marginal edges of the frame for receiving and supporting the smaller ends of 25 the springs of the intermediate set.

The main supporting frame, therefore, constitutes what may be termed the lower or spring supporting deck while the upper marginal rail is connected to the upper ends of the marginal 30 springs to assist in holding the latter in spaced relation.

One object of the invention is to provide what may be termed an intermediate resilient deck in about the same plane as the marginal rails 35 of the main supporting frame and engaging the intermediate portions of the springs of the inner set some distance from the ends thereof so that the portions of the springs of the intermediate set between the intermediate and upper deck may have greater resiliency than the portions between the intermediate deck and lower deck.

In other words, I have sought to obtain a gradually increasing resistance of the springs 45 of the inner set under pressure so that the upper portions of said springs above the intermediate deck will yield under comparatively light pressure while the portions below the intermediate deck will have greater resistance but 50 will gradually yield as the pressure upon the larger ends of the springs increases.

Another object is to connect the intermediate 55 portions of the springs of the inner set with each other and with the smaller ends of the springs of the outer set by means of additional coil

springs arranged in such manner as to normally hold the intermediate portions of the springs of the inner set in axial alignment with their lower and upper ends when the springs are subjected to pressure.

5 A further object is to provide the intermediate portions of the springs of the inner set with anchor members for attachment to the adjacent ends of the stay springs and to enable said members to be inserted between adjacent helices and turned to interlock therewith against lateral displacement.

Other objects and uses will be brought out in the following description.

In the drawings:

Figure 1 is a top plan of a portion of a spring mattress embodying the various features of my invention.

Figure 2 is a vertical sectional view taken in the plane of line 2—2, Figure 1.

Figure 3 is a perspective view of one of the detached anchor members.

Figure 4 is a vertical sectional view taken in the plane of line 4—4, Figure 1.

Figure 5 is an enlarged top plan of a modified 25 form of anchor plate shown as mounted upon the intermediate portion of one of the springs of the inner set and also showing the adjacent ends of the stay springs attached thereto.

Figure 6 is a top plan of a modified form of 30 anchor member attached to the intermediate portions of one of the inner springs.

Figure 7 is a detail vertical sectional view taken on line 7—7, Figure 6.

Figure 8 is a top plan of a further modified 35 form of anchor member shown as operatively mounted upon the intermediate portion of one of the inner springs and also showing the adjacent ends of the stay springs attached thereto.

As illustrated, this spring mattress comprises 40 a main supporting frame 1 constituting what may be termed the lower deck upon which is mounted an outer marginal set of coil springs 2 and an inner set of coil springs 2' having their upper ends disposed in substantially the same 45 horizontal plane parallel with that of the frame 1 for receiving and yieldingly supporting an upper marginal rail 3.

The main supporting frame 1 preferably comprises an outer marginal rail 4, lengthwise bars 50 5 and cross wire or rods 6, the bars 5 having their opposite ends secured by rivets 7 or equivalent fastening means to the upper faces of the opposite ends of the marginal rail 4 in spaced 55 parallel relation while the opposite ends of the

rods 6 are secured in a manner presently described to the corresponding sides of the rail 4, as shown more clearly in Figures 2 and 4.

The rail 4 is preferably made of angle iron 5 arranged with one of its flanges uppermost and extending outwardly, as shown more clearly in Figure 2, said rail being preferably continuous around the four sides of the mattress which may be of any desired form according to the use to

- 10 which it is put, but is shown as substantially rectangular with rounded corners, as shown in Figure 1 comprising one end of the mattress, it being understood that the other end will be of substantially the same form and construction 15 when the mattress is used as a bed or couch.

All portions of the marginal rail 4 are disposed in substantially the same plane, but the intermediate portions of the bars 5 and rods 6 are depressed some distance below or to one side of 20 the plane of the rail 4, as shown more clearly in Figures 2 and 4, the bar 5 being preferably rectangular in cross section and arranged with its intermediate portion edgewise vertically while its ends are arranged edgewise horizontally 25 to rest flatwise upon the upper surface of the rail 4.

The opposite ends of each of the rods 6 are looped downwardly around the lower edge of the rail 4 and upwardly across the outer edge of 30 said rail to firmly lock said rods against endwise movement relatively to the rail 4, the portions of said bars adjacent the inner and outer edges of the rails 4 being returned downwardly to form outer and inner loops 8 and 8' which project 35 slightly above the upper faces of the rail for receiving the adjacent smaller ends of the springs 2 of the outer set, as shown more clearly in Figure 4.

The depressed intermediate portions of the 40 rods 6 are provided with loops 9 extending under the lower edges and upwardly across the opposite sides of the bars 5 to hold their bars against lateral movement and also to assist in holding the rods against relative endwise movement, the 45 upper ends of the loops being extended slightly above the upper edges of the bars 5 and laterally therefrom to permit the lower ends of the intermediate springs 2' to be threaded thereon, as shown in Figure 4, thereby holding the lower 50 ends of these springs in fixed relation.

As previously stated, the upper rail 3 extends around the outer edges of the larger upper ends of the springs 2 of the outer set and is disposed in a plane substantially parallel with that of the 55 lower rail or deck 4 in vertically spaced relation thereto to permit said rail to be depressed toward the lower deck against the action of the springs, said rail 3 being attached to the adjacent portions of the springs 2 by means of metal clips 60 10, as shown more clearly in Figures 1, 2 and 4.

It will be noted upon reference to Figure 1 that the lower ends of the corner springs and side springs 2 of the outer set are mounted directly upon the upper faces of the rail 4 and that the lower ends of the corner springs are secured to 65 said rail by relatively short rods 11 similar to the opposite ends of the cross rods 6 in that they extend around the lower edge and upwardly along the opposite sides of the rail and having 70 their opposite ends returned to form loops 8 and 8' similar to those previously described on the ends of the rods 6 for receiving the lower helices of the adjacent springs and holding them in fixed relation to the rail.

75 The lower ends of the end springs 2 of the

outer set between the corner springs are mounted directly upon the upper faces of the adjacent ends of the bars 5 just inside of the adjacent end portions of the rail 4 and are secured thereto by rods 12 similar to but somewhat shorter than the rods 6 to hold said springs in fixed relation to the bars 5 of the lower deck of which they form a part as shown more clearly in Figures 1 and 2.

That is, the ends of the rods 12 are extended 10 under the lower faces of the adjacent ends of the bars 5 and are provided with loops 12' at opposite edges of the bars through which the lower ends of the adjacent springs are threaded, thereby assisting in holding the bars against lateral 15 movement and also holding the lower ends of the adjacent springs in fixed relation to the lower deck.

It will be noted upon reference to Figures 1, 2 and 4 that the springs 2 and 2' are arranged 20 in rows extending lengthwise and crosswise of the mattress in parallel spaced relation for freedom of yielding movement without interfering one with the other.

The upper or larger helices of the springs of 25 adjacent rows are yieldingly connected to each other by coil springs 13 which are arranged in pairs, each pair serving to connect adjacent sides of four of the coil springs 2 and 2'.

That is, the springs of each pair cross each 30 other diagonally and radially with reference to the coil springs connected thereby, the crossing portions being interlaced one with the other to bring them in substantially the same plane and also to increase the tension of the springs by 35 interlocking their intermediate portions one with the other, as shown more clearly in Figure 1.

An intermediate resilient deck 14 is normally supported in about the plane of the upper surface of the lower deck 1 parallel therewith and 40 comprises anchor members 15 and helical stay springs 16, 16' and 16'', and in view of the fact that the inner springs 2' of the inner set extend downwardly some distance below the upper surface of the lower deck, it is evident that the 45 intermediate resilient deck 14 will be disposed in a plane some distance from and between the lower and upper ends of the springs of the inner set.

It will be observed upon reference to Figures 50 2, 3 and 4 that the anchor members 15 are attached to the intermediate portions of their respective coil springs 2', this attachment being effected by providing each of the anchor members with a circular raised boss 17 seated within the adjacent helix of the corresponding spring in a manner presently described.

Each anchor member is also provided with a plurality of, in this instance four, radially projecting arms 18 arranged in uniformly spaced 60 relation circumferentially about the axis thereof, each arm being provided with an aperture 19 for receiving the adjacent ends of a corresponding number of pairs of the stay springs 16 and 16', see Figure 3.

The adjacent helices of the intermediate portion of each of the springs 2' engaged by the corresponding anchor member 15 are normally in close engagement with each other while the remaining helices of the same spring above and 70 below the anchor member are spaced a sufficient distance apart to permit said anchor member to be inserted radially therebetween and when the anchor member is thus inserted, it is turned about its axis to screw the arms 18 be- 75

tween the normally closed helices so that the tension of the latter toward each other tends to hold the anchor member in its adjusted position with the raised boss within the adjacent portion of the spring, thereby locking the spring and anchor member to each other against relative lateral movement.

Under these conditions, the radial arms 18 project beyond the periphery of the adjacent portion of the spring diagonally of the transverse and lengthwise rows of springs, as shown more clearly in Figure 1.

The springs 16 are arranged in pairs, those of each pair serving to connect the lower or smaller end of one of the outer set of springs 2 with two of the arms 18 on the next adjacent intermediate spring 2'.

The springs 16' are also arranged in pairs and serve to connect adjacent pairs of arms 18 of the anchor members 15 of adjacent springs 2' of each transverse row of said intermediate springs.

In like manner, the springs 16'' are arranged in pairs, those of each pair extending lengthwise of each lengthwise row of springs 2' and are connected to adjacent pairs of the arms 18 of the anchor members 15 of the intermediate springs.

It will now be observed that the intermediate portions of the springs 2' of each transverse row are yieldingly connected to each other through the medium of the springs 16' and their corresponding anchor members 15 and that the lower ends of the outer springs 2 of the same transverse row are yieldingly connected to the anchor members 15 on the intermediate portions of the adjacent inner springs 2' so that the springs 16 and 16' constitute parts of the intermediate resilient deck.

In like manner, the intermediate portions of the springs 2' of each lengthwise row are yieldingly connected to each other through the medium of the stay springs 16'' and anchor members 15 which also form parts of the intermediate resilient deck 14.

It will be noted upon reference to Figure 1 that the lower end of each of the springs of the outer marginal set, except those at the corners, is connected by two stay springs 16 to the intermediate portion of the adjacent spring 2' of the intermediate set and that the springs 16 extend along the cross rods 6 and lengthwise bars 5 and, therefore, the transverse stay springs 16 of each pair will extend at substantially right angles to those along the lengthwise bars, the function of which is to yieldingly hold the intermediate portions of the springs of the inner set coaxial with the opposite ends or rather against undue inward movement.

The stay springs 16' connecting the intermediate portions of adjacent springs 2' of the inner set also serve to yieldingly hold the intermediate portions of the springs 2' against lateral movement or co-axial with their opposite ends.

In like manner, the lengthwise stay springs 16'' connecting the intermediate portions of adjacent inner springs 2' coacting with the opposite or outer set of springs 16 serve to hold the intermediate portions of the inner springs coaxial with their opposite ends against relative lateral movement.

Under this arrangement, the springs 2' of the intermediate set are all yieldingly tied to each other through the medium of the stay springs

16' and 16'' and anchor members 15 and are also yieldingly connected to the lower ends of the springs 2 of the outer set through the medium of the stay springs 16, thus permitting the outer or larger ends of the intermediate springs 2' to flex axially under relatively light pressures, which flexing action is continued through the lower portions of the intermediate springs as the pressure on the larger ends increases, each intermediate spring being free to flex axially independently of each other and also independently of the springs 2 of the outer set.

When the pressure upon the larger ends of the springs is excessive, this pressure is transmitted to the lower deck which is yieldingly supported by the lower ends of the springs 2' below the corresponding anchor members 15, thereby affording a highly resilient spring mattress capable of responding to light or heavy pressures and also capable of self-restoration to their normal positions when the pressure is removed.

It will be seen from the foregoing description, particularly upon reference to Figure 1, that each arm 18 of each anchor member is adapted to receive the adjacent ends of two stay springs or in other words, each anchor member is adapted to receive the adjacent ends of eight stay springs.

The outer ends of the stay springs 16 are provided with eyes or hooks adapted to engage the inner sides of the lower ends of the corresponding springs 2 of the outer set while their inner ends are provided with similar hooks adapted to be attached to the corresponding arms 18 of adjacent anchor members for the springs of the inner set.

The anchor member 15 preferably consists of a metal plate having its central portion pressed upwardly to form the boss 17.

In Figure 5 I have shown a modified anchor member consisting of a metal plate 15' having radial arms 18 similar to those shown in Figure 3, the boss 17 being omitted and the central portion cut away to form an opening 20, said plate being provided with a plurality of, in this instance four, lugs 21 arranged in uniformly spaced relation circumferentially between the arms 18 and preferably overturned inwardly upon one of the intermediate helices of the spring 2' to hold the plate and spring against relative lateral movement.

In Figure 6 is shown a further modified form of anchor member 15'' consisting of a single piece of wire bent into rectangular form and the corners thereof deflected outwardly to form loop-shaped arms 18' for receiving the adjacent ends of the stay springs 16' and 16'', the ends of the wire anchor member being secured together at 22.

The portions of the arms 18' extending across opposite sides of the intermediate portion of the spring 2' are bent downwardly to form loops 23 which receive the adjacent portions of the spring 2' to hold the anchor member and spring against relative lateral movement, see Figure 7.

In Figure 8 is shown an anchor member 15''' which also consists of a single piece of wire bent into more or less circular form and provided with radially projecting looped arms 18'' for receiving the adjacent ends of the stay springs 16' and 16'', the portions of the anchor member between the arms being overturned outwardly at 24 upon the adjacent helix of the intermediate portion of the spring 2' to hold the

anchor member and spring against relative lateral movement.

All of these modified anchor members are found to be a practicable equivalent of that shown in Figure 3 to serve the same purpose and may also be inserted between the closely arranged helices of the spring 2' in the manner previously described.

A spring mattress constructed in the manner described is strong, durable and highly resilient for light and heavy weights or pressures and while it is particularly adapted for beds, couches, lounges and analogous pieces of furniture, it may be used for chairs and other seats or for the backs of any upholstered article, and in all of such uses the springs of the outer set as well as those of the inner set will be maintained in substantially parallel relation.

It is also evident that the upper marginal rail 3 and larger ends of the outer set of springs to which it is attached is free to yield laterally in all directions under corresponding pressures with the assurance that they will be self-restoring to their normal upright positions with the axes of the springs substantially at right angles to the main supporting frame 4.

Some change may be made, however, in the detail construction of the various parts of the mattress without departing from the spirit of the invention.

What I claim is:

1. A spring mattress comprising, in combination, a frame, a coil spring mounted on the frame, an anchor member attached to the intermediate portion of the spring and provided with a plurality of arms arranged in uniformly spaced relation about the axis thereof, each arm having a pair of stay-springs attached at one end thereto at a common point and their other ends at-

tached to the arms of similar anchor members of adjacent springs.

2. A spring mattress comprising, in combination, a frame, inner and outer sets of coil springs mounted on the frame, separate anchor members inserted between intermediate helices of the springs of the inner set and each provided with a plurality of radial arms arranged in spaced relation about the axis thereof, divergent stay-springs connecting certain arms of the anchor members with adjacent springs of the outer set, and additional stay-springs connecting the same arms to the arms of similar anchor members of adjacent springs of the inner set.

3. In a spring mattress, the combination with a frame and a coil spring mounted thereon, of an anchor member removably inserted between intermediate helices of the spring and provided with a plurality of radial arms arranged in spaced relation about the axis thereof, and separate pairs of stay-springs, one pair for each arm and those of each pair connecting its corresponding arm with the arms of similar anchor members of adjacent springs.

4. A spring mattress comprising a frame, outer and inner sets of coil springs mounted on the frame to extend upwardly therefrom, and anchor members interposed between adjacent intermediate helices of the springs of the inner set and each provided with four radial arms arranged in uniformly spaced relation about the axis thereof, each arm having a pair of helical stay springs attached thereto, some of the stay springs being attached to the adjacent springs of the outer set and others connecting the adjacent arms of the anchor members.

WILLIAM LEWIS.
